(57) **CLAIM**

The ornamental design for a cover for liquid dispenser, as shown and described.

DESCRIPTION

This application is related to co-pending Ser. No. 29/483,438, which is incorporated by reference herein.

FIG. 1 is a top, side and front perspective view of a cover for liquid dispenser in the closed position showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view, the right side being a mirror image thereof;

FIG. 7 is a cross-sectional view taken along line 7-7 of FIG. 2;

FIG. 8 is a top, side and front perspective view of a cover for liquid dispenser in the open position showing our new design;

FIG. 9 is a top plan view thereof;

FIG. 10 is a bottom plan view thereof;

FIG. 11 is a front elevation view thereof;

FIG. 12 is a rear elevation view thereof; and,

FIG. 13 is a left side elevation view, the right side being a mirror image thereof.

1 Claim, 6 Drawing Sheets
